(57) **CLAIM**

The ornamental design for an article of jewelry as shown and described.

DESCRIPTION

FIG. 1 is a front perspective view of the article of jewelry; FIG. 2 is a front view thereof; FIG. 3 is a back view thereof; FIG. 4 is a right view thereof; FIG. 5 is a top view thereof; and, FIG. 6 is a back isometric view thereof.

The left view has been omitted as it is a mirror image of the right view in FIG. 4. The bottom view has been omitted as it is identical to the top view in FIG. 5. The broken lines in the drawings are provided to show features and boundaries that form no part of the claimed design. The surfaces adjacent to both solid and broken lines show portions of the article that form no part of the claimed design.
